VENTILATION OF HOUSES

William C. Coulton, Medford, Mass., assignor of
one-eighth to Albert A. Stearns, Brooklyn, N. Y.

Application September 29, 1934, Serial No. 746,193

4 Claims. (Cl. 98—32)

This invention relates to the ventilation of houses and has special reference to building construction adapted to provide automatic ventilation of the various rooms of a building.

5 One important object of the invention is to provide an improved building construction wherein the ventilating means are so arranged as to render the building interior proof against the entry of moisture from the exterior under all 10 climatic conditions.

A second important object of the invention is to provide an improved building construction whereby great economy of heating may be effected in the colder periods of the year and the 15 interior of the building be prevented from becoming excessively hot during the warmer portions of the year so that a great saving of fuel is effected during each cold period.

A third important object of the invention is 20 to provide means in a building construction whereby the windows may be kept closed and yet such building be well ventilated.

A fourth important object of the invention is 25 to provide an improved ventilation system especially adapted to prevent the introduction of dust into the rooms of the building thereby keeping the interior walls clean and avoiding the necessity of frequent repapering and repainting.

With the above and other objects in view, the 30 invention consists in general of certain novel details of construction and combinations of parts hereinafter fully described, illustrated in the accompanying drawings and specifically claimed.

In the accompanying drawings like characters 35 of reference indicate like parts in the several views, and:—

Figure 1 is a transverse section on the line 1—1 of Figure 3 through a building typically indicating the construction of the invention.

40 Figure 2 is a section approximately on line 2—2 of Figure 1.

Figure 3 is a section approximately on line 3—3 of Figure 1.

45 Figure 4 is an enlarged detail section through the upper part of the building showing the manner of controlling the draft.

Figure 5 is a section on line 5—5 of Figure 4.

Figure 6 is an enlarged detail section showing the manner of supplying air between the outer 50 and inner window frames.

Figure 7 is a detail showing the up take draft for supplying air through the space between the outer and inner window frames.

55 Figure 8 is a sectional view showing the baffle plate in place.

In carrying out the present invention there is provided a building having a foundation wall 10 on which is erected an outer masonry wall 11 and an inner wall consisting of studding 12 on the outer side of which is arranged in spaced relation to the masonry wall, a suitable coating or sheeting 13 while on the inner side thereof there is erected the usual lath and plaster suitable to be covered by paper or paint. Thus there is provided an outer wall and an inner wall 10 spaced from each other so that there is an air space between them. In the basement of the building, above the foundation wall 10, there is provided the outer window but the window may be double so that there is an outer cellar window 15 and an inner cellar window 16. The outer cellar window being provided with a vent 17 through which air blows into the space between the two windows above described. The inner wall terminates upwardly at the attic floor 18. 20 This same arrangement is made on each floor, that is to say, air is admitted on each floor in the manner just described, through the spaces between the outer and inner walls.

As is usual in building intended for human 25 occupancy there is provided a chimney 19 which is surrounded by a wall 20 spaced for the chimney so as to provide flues 21 communicating with the atmosphere through ducts 21'. In the upper story of the attic of the house it will be 30 observed that all of the air going up between the inside and outer wall will collect, and vents 22 are provided in the outer wall surrounding the chimney so that the hot and foul air may pass through these flues. There is also provided, 35 through each set of rooms, vertical bearing partitions 23 having air spaces in them communicating at the bottom to the cellar and to the atmosphere through ducts 23' and at the top to the attic space. In these partitions there are provided just below the ceiling of each floor, vents 24 to take off the dead air.

Furthermore there may be provided, as shown in Figure 4, a vertical chamber 25 wherewith the exhaust air ducts communicate so that all the 45 exhaust air is accumulated in this chamber and a damper 26 is preferably arranged at the top of the chamber communicating with a four way hood 27 so designed to prevent back pressure of wind or from any draft or wind and to induce 50 draft from the chamber 25. If desired an exhaust fan may be used to cause a forced draft.

Between the vertical outer and inner walls as shown in Figure 6 there may be a steam heating coil consisting of a steam inlet pipe 28 and an 55

outlet pipe 29. Also a heater 30 may be placed in the inlet duct 31 as shown in Figure 1 at the lower left hand portion of the building. A baffle plate 32 may be placed below the heater in the space between the two walls to filter out the dirt and dust and thus cleanse the air as it rises up.

Arranged in the window trim at each side of the window openings are vents 33 controlled by shutters to admit fresh air in the room. Thus 10 the rooms can be ventilated very efficiently even with closed windows.

There has thus been provided a simple and efficient construction of the kind described and for the purpose specified. A constant circulation 15 of air throughout the building will be formed and there will be no dead air spaces whatever. The windows set in the outer wall can be closed tight yet sufficient air through the openings 33 in the sides of the window frames will flow in the rooms 20 to give adequate ventilation. A home according to this disclosure has actually been built and it has been found that the interior is much cooler in the summer time and greatly more comfortable than the ordinary home. Also in the winter time 25 the home can be kept warm at a saving of approximately 50% of the fuel bill.

It is obvious that changes may be made in the specific form and arrangement of the construction without departing from the principles of the 30 invention and therefore it is not desired to confine the invention to the exact form therein shown and described but it is wished to include all such as come within the scope of the appended claims.

What is claimed is:

35 1. In a building construction of the class described, outer and inner walls spaced to provide ventilating spaces, means including openings to admit air at the lower outer parts of said walls, said walls including window openings and frames

therefor, said frames straddling both of said outer and inner walls, said frames provided with openings registering with the space between the said walls to provide ventilation for the said space.

2. In a building construction of the class described, outer and inner walls spaced to provide ventilating spaces, means including openings to admit air at the lower outer parts of said walls, said walls including window openings and frames therefor, said frames straddling both of said outer and inner walls, said frames provided with openings registering with the space between the said walls to provide ventilation for the said space, and a baffle plate above the said openings to clean and filter the air before it reaches the 15 interior of the building.

3. In a building of the class described having outer and inner walls spaced to provide ventilating spaces, partitions in said building, the walls of said partitions being hollow, ducts from the exterior of said building leading to the interior of said hollow partitions, all of said partitions and ducts being arranged so that the air passing therethrough is collected in one compartment, and means in said compartment to allow the stale 25 air to flow out to the atmosphere.

4. In a building of the class described having outer and inner walls spaced to provide ventilating spaces, partitions in said building, the walls of said partitions being hollow, ducts from the 30 exterior of said building leading to the interior of said hollow partitions, all of said partitions and ducts being arranged so that the air passing therethrough is collected in one compartment, means in said compartment to allow the stale air 35 to flow out to the atmosphere, and means to control the outflow of air.

WILLIAM C. COULTON.
